THERMOSTATICALLY CONTROLLED FUEL
ENRICHMENT DEVICE

William E. Haast, Hawthorne, N. J.

Application May 3, 1939, Serial No. 271,465

1 Claim. (Cl. 123—119)

This invention relates to internal combustion engines and more particularly to thermostatically controlled fuel enrichment devices for automobiles.

- 5 Automatic chokes now in use are usually controlled directly by the heat from the exhaust gases. Due to the extreme variations in temperature, chokes controlled in this manner fail to function properly after a short period of time.
- 10 This is usually due to a permanent distortion of the thermostatic element as a result of the high exhaust temperatures. The general object of my invention is to provide a fuel enrichment device thermostatically controlled by the cooling
- 15 water temperature whereby the maximum temperature reached would be approximately 212 degrees Fahrenheit. Another object of my invention is to provide a dual means for fuel enrichment whereby the admission of gas to the intake manifold is independent of the opening or closing of the throttle. In short I propose to introduce an additional supply of gas either through an auxiliary nozzle located in the Venturi section of the carburetor above the throttle butterfly valve when open, or by admitting gas into the manifold directly below the throttle butterfly when closed. In both cases the additional gas supply will be controlled by a thermostatic valve actuated by the changes in temperature of the
- 20 cooling water.

The full objects and advantages of my invention will appear in the detailed description when studied in conjunction with the drawing, and the novel features of the invention are pointed out

25 in the appended claim.

In the drawing illustrating my invention,—

Fig. 1 is a front elevational view partly in section showing the proposed fuel enrichment system.

40 Fig. 2 is an enlarged side elevational view of the U shaped bracket.

Fig. 3 is an enlarged side elevational view of the thermostat and needle valve stem.

In detail a carburetor 1 is provided with a 45 standard fuel feed nozzle 5 connected to the float reservoir 2 and positioned in a venturi 3. The air enters through the strainer 4 and passes down through the venturi 3 where it picks up gas from the nozzle 5 to form a combustible mixture. Said mixture is then drawn past the open butterfly valve 6 into the intake manifold connection 7, and on into the cylinders of the

50 motor.

The proposed thermostatically controlled device allows an additional supply of fuel to enter

the intake either through the auxiliary nozzle 12 in the Venturi section or the idling nozzle 14 located below the throttle butterfly 6. During the interval of starting the motor and the short period after starting and while the motor is still cold the operator may either close or open the throttle by operating the accelerator. When the accelerator is depressed the motor draws air through the strainer 4, and past the standard feed nozzle 5. The rush of air passing the nozzle 5 picks up gas from said nozzle to form a combustible mixture. In the operation of starting the motor the speed is usually so slow, and consequently the suction so low, that an insufficient amount of gas for starting a cold motor is picked up from the standard nozzle 5. By providing an auxiliary nozzle 12 relatively in the same position in the venturi as the main fuel nozzle 5, and adapted to work in conjunction therewith during the period the motor is cold, a greater supply of 20 gas is provided for starting the cold motor due to the additional nozzle.

On the other hand if the accelerator is not depressed, so little air will be drawn past the nozzles 5 and 12 that there will be insufficient 25 fuel to form a rich enough mixture for starting a cold motor. In that case the butterfly 6 will remain closed and any suction or negative pressure developed by the motor will be confined to the manifold below the butterfly throttle. The idling nozzle 14 being located in the section of the intake manifold below the butterfly 6, will be under suction and as a result gas will be drawn through the fuel line 13 to provide a rich 30 enough mixture for starting or running during the idling period of a cold motor.

The thermostatic fuel valve to which the auxiliary nozzles 12 and 14 are connected by fuel lines 11 and 13, controls the period over which 35 gas will be fed to said nozzles. In other words the needle valve comprising stem 18 and seat 23 will remain open while the motor is cold, and as the cooling water in the block is heated the valve will close and the fuel enrichment effect 40 will stop. The valve 9 comprises a main bushing 15 adapted to fit into the motor block 16. A thermostatic bellows 17 is carried on a U shaped bracket 19 and projects through the top of the motor block 16 into the water jacket space 20. 50 The bracket feet 25 are detachably fastened to the base of the bushing 15. By this type of assembly the thermostatic element can be readily replaced if desired. A valve bushing 22 provided with the needle valve seat 23 is sealed in 55

the top of the main bushing 15 thereby providing a chamber 24 for the gas. The auxiliary supply line 10 supplies gas from the carburetor reservoir 2 to the chamber 24 of the valve 8. If the motor 5 is cold the needle valve 18 remains off its seat 23 and the gas is thereby permitted to flow through the auxiliary feed lines 11 and 13 to the auxiliary nozzles 12 and 14.

As explained above when the butterfly valve 6 is open, gas will be drawn from the main nozzle 5 and in addition a surplus supply necessary for starting a cold motor will be drawn from the auxiliary nozzle or orifice 12 at the same time. On the other hand if the butterfly valve 6 is closed, the suction produced in the manifold between the butterfly valve 6 and motor, where the idling nozzle 14 is located, will draw gas through the fuel line 13 into the motor as long as the thermostatic valve 9 is open during cold motor temperatures. Further, in the first case, that is when the butterfly valve 6 is open, in addition to gas being drawn from the main nozzle 5 and auxiliary nozzle 12, fuel is also drawn into the manifold from nozzle 14 due to the slight

negative pressure set up in the manifold even when the throttle is open.

I claim:

A fuel enrichment device for water cooled motors comprising a standard carburetor provided 5 with a venturi, a butterfly throttle valve adjacent the carburetor at the entrance to the intake manifold, a main fuel supply nozzle located in said venturi and connected through the main fuel supply line directly to the carburetor, an auxiliary 10 fuel nozzle located in the venturi for the enrichment of the fuel supply when the throttle is open and during cold motor operations, an auxiliary fuel nozzle located in the intake manifold adjacent said butterfly valve for the enrichment 15 of the fuel supply during cold motor operation with a closed throttle, an auxiliary fuel supply line connecting said auxiliary fuel nozzles to the carburetor, and a thermostatically operated valve in the auxiliary fuel supply line actuated by the 20 change in temperature of the motor cooling water for cutting off the supply of fuel to said auxiliary nozzles when the motor warms up.
